Primary Examiner — Kevin Rudzinski*Assistant Examiner* — John Reickel(74) Attorney, Agent, or Firm — NSIP Law(57) CLAIM

The ornamental design for a display screen or portion thereof with graphical user interface, as shown and described.

DESCRIPTION

The sole FIGURE is a front view of a display screen or portion thereof with graphical user interface, showing my new design.

The broken line showing of a display screen and elements of a graphical user interface are included for the purpose of illustrating portions of the article and form no part of the claimed design.
